UNITED STATES PATENT OFFICE.

FORD W. HARRIS, OF WILKINSBURG, PENNSYLVANIA, ASSIGNOR TO WESTINGHOUSE ELECTRIC AND MANUFACTURING COMPANY, A CORPORATION OF PENNSYLVANIA.

CIRCUIT-INTERRUPTER.

1,113,433.

Specification of Letters Patent. Patented Oct. 13, 1914.

Application filed October 8, 1910. Serial No. 586,095.

To all whom it may concern:

Be it known that I, FORD W. HARRIS, a citizen of the United States, and a resident of Wilkinsburg, in the county of Allegheny 5 and State of Pennsylvania, have invented a new and useful Improvement in Circuit-Interrupters, of which the following is a specification:

My invention relates to circuit interrupters for electric circuits and it has 10 special reference to interconnecting mechanisms for a plurality of circuit interrupters.

The object of my invention is to provide 15 a simple and effective interconnecting mechanism for a plurality of interrupters that shall be particularly adapted to effect a concurrent opening of said interrupters under predetermined conditions, but which will 20 permit of separate and independent closure thereof.

My invention may best be understood by reference to the accompanying drawings, in which—

Figure 1 is a view in side elevation of a circuit interrupter which embodies my invention, and Fig. 2 is a view in front elevation of the lower portions of two circuit interrupters which are rendered interdependent by means of an interconnecting mechanism which embodies my invention. In both figures, certain portions of the interrupters are either broken away or omitted.

Referring to the drawings, the device here 35 illustrated comprises a plurality of circuit interrupters 1 and 2 of like construction, each of which comprises a pair of stationary contact terminals 3 and 4, a movable bridging contact member 5, a pair of arcing contact members 6 and 7, an operating mechanism 8, tripping magnet 9, a tripping member 10 and an interconnecting mechanism 11.

The stationary contact terminal 3 is 45 mounted upon an insulating slab or panel 12 and is provided with an upwardly projecting trough-shaped member 13, to receive the arcing contact member 6. The stationary contact terminal 4 is also secured to the insulating panel 12 and is located directly below the stationary contact terminal 3. The stationary contact terminal 4 is electrically connected to a conductor 14 of relatively few turns which is adapted to conduct comparatively large currents and constitutes the exciting winding 15 of the tripping magnet

9. All of the movable parts of the interrupter are mounted upon stationary shafts 16, 17 and 18 which are supported by bracket plates 19 and 20 upon the insulating panel 12.

The movable bridging contact member 5 comprises a plurality of relatively thin strips 21 of copper which are held together in position by curved clamping plates 22 and 23. The outer clamping plate 23 is provided with a downwardly projecting arm 24, the lower end of which is pivotally supported upon the shaft 18. A member 25 is pivotally secured to the outer clamping plate 23 by a pin 26, and the upper end of said member carries the arcing contact member 7 which is adapted to coöperate with the arcing contact member 6. The operating mechanism 8 comprises an operating lever 30 which is mounted upon the shaft 16 and has an insulating handle 31 at its outer end and a curved inner end 32 for a purpose to be hereinafter explained.

A bell crank lever 33, comprising two double arms 34 and 35 and projections 37 and 38, is pivotally mounted upon the shaft 16. A roller 36 is mounted upon a pin 36^a between the arms 35 of the bell crank lever 33 and helical springs 39 are connected between the projections 37 and the lower end of the member 25. A stop 40 is provided upon bracket plate 19 to be engaged by the projection 38 of the bell crank lever 33 in order to limit the movement of said bell crank lever 33 in a clockwise direction. The upper ends of the arms 34 are pivotally connected to the lower end of a link 42, the upper end of which is secured to the member 25 and the movable contact member 5 by the pin 26. The relative proportions and the arrangement and location of parts is such that, as the circuit interrupter is opened, the bridging contact member 5 is separated from the coöperating stationary terminals 3 and 4 prior to the final interruption of the circuit which is confined to the arcing contact members 6 and 7, as will be readily understood.

The tripping magnet 9 comprises a stationary core member 45, the exciting winding 15 and a movable core member 46 which is secured to the inner end of a movable member 47. The movable member 47 is provided with upwardly projecting arms 48 and 49 which are pivotally supported upon the shaft 17 and which carry an adjustable trig-

ger 50, an adjustable weight 51, a scale 52 to indicate positions of said weight, and a weight-adjusting screw 53.

The tripping member 10 is pivotally mounted upon the shaft 17 and is provided with a downward extension 54 which is adapted to be engaged by the trigger 50, when the tripping magnet 9 is sufficiently energized. The member 10 is also provided with a latch 55 to engage the roller 36 and retain the operating mechanism in its closed position, and an upwardly projecting arm 56 to engage a stop pin 57 in order to restrict movement of the tripping member 10 in a counter-clockwise direction. A spring 58 surrounds the shaft 17 and the opposite extremities of said spring are respectively secured to the tripping member 10 and the stop pin 57. The object of spring 58 is to maintain the latch 55 in engagement with the roller 36.

The interconnecting mechanism 11 comprises an auxiliary tripping member 59 having two arms 60 and 61 which are joined together at their inner ends by a connecting web 62 and at their outer ends by a web 63. The arm 61 of the auxiliary tripping member 59 is pivotally supported upon the shaft 17 and projects upwardly to engage the stop pin 57. The arm 60 of the auxiliary tripping member 59 is provided with a laterally projecting member 66, between which and the stop pin 57 is connected a coil spring 67 to maintain said auxiliary tripping member 59 normally in its upper position.

A catch 68 is pivotally mounted between the outer ends of the arms 60 and 61, upon a pin 69. As shown, the catch 68 is U-shaped and is maintained in engagement with the web 63 by a spring 70 which surrounds the pin 69. It will be observed, therefore, that clockwise rotation of the catch 68 is impossible, whereas counter-clockwise rotation thereof may be accomplished in opposition to the action of the spring 70. It will also be observed that the upper edges 71 of the catch 68 are slightly inclined to the horizontal for a purpose to be hereinafter set forth. A connecting bar 72 is rigidly secured to the outer ends of all the auxiliary tripping members 59, and, hence, said members are rendered interdependent and must move concurrently.

Assuming the various pieces of apparatus to occupy the positions shown in the drawings, the operation of the device illustrated is as follows: When the current traversing the magnet coil 15 exceeds a predetermined amount, the movable core member 46 is attracted to the stationary core member 45 and rotative movement is therefore imparted to the movable member 47. As the movable member 47 is thus moved in a clockwise direction, the trigger 50 engages the downward extension 54 of the tripping member 10 and

thereby causes the latch 55 to be disengaged from the roller 36. The operating mechanism 8 is therefore released and the weight of the interrupter parts and the action of the springs 39 cause the toggle, formed by the connecting link 42 and the arms 34 of the bell crank lever 33, to collapse, thereby effecting the separation of the coöperating movable and stationary contact members. As the toggle collapses, the arms 35 of the bell crank lever 33 are moved in a counter-clockwise direction, and, in so doing, come into engagement with the inclined upper edges 71 of the catch 68. Inasmuch as clockwise movement of the catch 68 is prevented, the auxiliary tripping member 59 is forced downwardly by reason of the engagement of the arms 35 of the bell crank lever with the inclined edges 71 of the catch 68. It is evident that the downward movement thus imparted to the auxiliary tripping members 59 of the circuit interrupter 1 is also transmitted to the tripping member 59 of the circuit interrupter 2, by reason of the rigid connecting member 72. On account of the engagement of the webs 62 with the downward extensions 54 of the tripping members 10, any downward movement of either auxiliary tripping member 59, effects the release of the latches 55 from the rollers 36. Hence, it will be readily understood that approximately concurrent opening of interrupters 1 and 2 is effected.

In case manual operation is desired, the operating lever 30 may be raised to its uppermost position, thereby causing the extremity of the extension member 32 to engage a portion 73 of the tripping member 10, and thus release the latch 55 from the roller 36. The remainder of the opening operation is similar to that hereinbefore described and will be readily understood by those skilled in the art. Assuming the circuit interrupter to be opened, the operation of closing is as follows: The operating handle 31 is forced downwardly to its extreme lower position, thereby causing the curved extension member 32 to engage the lower end of the connecting link 42 and force the toggle, formed by said connecting link and the arms 34 of the bell crank lever 33, nearly into its dead center position. This action causes a successive closure of the arcing contact members 6 and 7 and the coöperating bridging contact member 5 and the stationary contact terminals 3 and 4. It will be observed that, as the bell crank lever member 33 is caused to rotate in a clockwise direction during the closing operation, the lower ends of the arms 35 come into engagement with the catch 68. However, as the counter-clockwise rotation of said catch is unrestricted, except by the action of the spring 70, said catch is merely rotated upon its shaft 69, thus allowing the

bell crank lever member 33 to pass without imparting any movement to the auxiliary tripping members 59. It is therefore evident that separate and independent closures of 5 circuit interrupters 1 and 2 may be effected.

Although I have shown an interconnecting mechanism as applied to two circuit interrupters of a particular type, it will be understood, by those skilled in the art, that 10 any number of interrupters may be so interconnected and that my invention is not restricted to circuit interrupters of any particular construction.

Many modifications in the structural 15 details and in the arrangement and location of parts may be effected within the scope of my invention and I desire that only such limitations shall be imposed as are indicated in the appended claims.

20 I claim as my invention:

1. The combination with a plurality of circuit interrupters having individual automatic tripping devices and individual operating handles, of means associated with 25 each handle for actuating its associated tripping device, and means for interconnecting said devices to secure concurrent opening of said interrupters and for permitting said interrupters to be closed separately.

2. The combination with a plurality of circuit interrupters, and means for effecting concurrent automatic opening thereof and for permitting independent closure of said 35 interrupters, of means associated with the operating handle of each interrupter for manually effecting a concurrent opening of all of said interrupters.

3. The combination with a plurality of 40 circuit interrupters, each provided with an operating mechanism and handle, a latch to restrain said mechanism, and a tripping device and magnet to release said latch, of means associated with each handle for releasing said latch, an intermediate member 45 associated with each interrupter and adapted to be actuated by said operating mechanism to release said latch, and an interconnecting means for securing concurrent action 50 of said intermediate members.

4. The combination with a plurality of circuit interrupters each provided with an operating mechanism and handle, means for restraining said mechanism, an automatic 55 tripping device to release said restraining means and means associated with said handle for releasing said restraining means, of an interconnecting mechanism associated with each interrupter and adapted to be 60 actuated by any interrupter to release said restraining means of all interrupters.

5. The combination with a plurality of circuit interrupters, each comprising co-operating stationary and movable contact members, an operating mechanism and 65 handle for said movable members, means for restraining said operating mechanism, automatic means for releasing said restraining means and means associated with said handle for releasing said restraining means, 70 of mechanical means dependent upon the opening of any interrupter for releasing said restraining means of the remaining interrupters, and means associated with said mechanical means for permitting independent 75 closure of said interrupters.

6. The combination with a plurality of circuit interrupters, each comprising co-operating stationary and movable contact members, an operating mechanism for said 80 movable members and an operating handle therefor having a latch-engaging projection, of a tripping magnet and movable core member therefor, a latch to restrain said operating mechanism and to be released by 85 said movable core member or said projection, a pivotally supported auxiliary member also adapted to release said latch, a catch member pivotally mounted upon the free end of said auxiliary member and capable of rotative movement in one direction only and also adapted to be engaged by said operating mechanism when said interrupter is opened or closed, and means for interconnecting all of said auxiliary members. 95

7. The combination with a plurality of circuit interrupters, automatic means associated with each interrupter for effecting its release, and means interconnecting parts of each automatic means, of means associated with each interrupter and co-operating with parts of said automatic releasing means for manually effecting the release of all said interrupters. 100

8. In an electrical protective device a 105 plurality of circuit interrupters severally comprising a toggle mechanism, a latching device for said toggle mechanism, automatic means for tripping said latching device, an operating handle for said toggle mechanism 110 and for manually tripping said latching device, and means actuated by the toggle mechanism of one of the said interrupters to concurrently trip the latching devices of the other interrupters. 115

In testimony whereof, I have hereunto subscribed my name this 29th day of Sept. 1910.

FORD W. HARRIS.
